Primary Examiner — Cynthia Ramirez*Assistant Examiner* — Michael A Maharajh*(74) Attorney, Agent, or Firm* — Seed Intellectual Property Law Group LLP(57) **CLAIM**

The ornamental design for a locking collar, as shown and described.

DESCRIPTION

FIG. 1 is a top, front left perspective view of a locking collar showing our new design.

FIG. 2 is a bottom, rear right perspective view thereof.

FIG. 3 is a left side elevation view thereof.

FIG. 4 is a right side elevation view thereof.

FIG. 5 is a top plan view thereof.

FIG. 6 is a front elevation view thereof.

FIG. 7 is a rear elevation view thereof.

FIG. 8 is a bottom plan view thereof; and,

FIG. 9 is a top plan view of the locking collar of FIG. 1, with the clamping fastener shown in an extended position.

The broken lines shown in the figures are for the purpose of illustrating portions of the locking collar that form no part of the claimed design.

1 Claim, 7 Drawing Sheets(56)
